3,027,500 WIDTH CONTROL

Bernard J. Smith, Syracuse, N.Y., assignor to General Electric Company, a corporation of New York
Filed July 20, 1959, Ser. No. 828,325
3 Claims. (Cl. 317—200)

This invention relates to a width control for use in television receivers in which the scanning of the cathode ray beam in the picture tube is controlled by a magnetic deflection yoke.

Whereas the vertical dimension of the image can be controlled by the simple expedient of connecting a potentiometer in the circuit of the vertical oscillator, it has been customary to control the horizontal dimension by inserting a rather expensive variable inductor in the horizontal deflection circuit.

As the deflection angle of the cathode ray tubes has been increased, the diameter of the portion inside the deflection yoke has been decreased to such a degree to conserve power that the electron beam often grazes the inner surface of the tube wall causing emission of electrons therefrom that eventually reach the phosphor screen in a random manner so as to reduce the contrast ratio of the image.

One of the limitations of the shortness of the cathode ray tube is the proximity of the yoke to the focusing electrode of the electron gun because the magnetic fields of the yoke will cause a marked defocusing of the beam and a consequent loss of detail in the image.

It is an object of this invention to provide an inexpensive means for controlling the width of the area scanned by the electron beam of a cathode ray tube in response to the magnetic fields produced by a deflection yoke.

It is another object of this invention to provide a width control for an electromagnetically deflected electron beam that improves the contrast of the images formed by the beam in cathode ray tubes where the beam tends to graze the inner surface of the tube.

It is still another object of this invention to provide a width control for an electromagnetically deflected electron beam of a cathode ray tube that also reduces the deleterious effect of the electromagnetic field of the focus of the beam.

Briefly these objectives may be attained in accordance with the principles of this invention by mounting tabs of highly permeable material close to the rear of the horizontal deflection coils of the deflection yoke in such manner that they can be adjusted in a direction perpendicular to the axis of the tube.

The manner in which this is done will be more apparent after the following discussion of the drawings in which:

FIGURE 1 shows a single deflection coil of "saddle" configuration.

FIGURE 2 is a view of a magnetic deflection yoke mounted on the neck of a cathode ray tube having the tabs of the invention incorporated therein;

FIGURE 3 is an axial view from the rear of the deflection yoke taken at section AA; and showing the tabs in a position to reduce the width of the area scanned;

FIGURE 4 is similar to FIGURE 2 except that it shows the tabs in a position that permits an increased width of the area scanned;

FIGURE 5 is a cross sectional view in a plane through the axis of the yoke showing certain details of the structure for retaining the tabs in position.

FIGURE 6 shows the detail of a frame also shown in FIGURE 4 for retaining the tabs in position; and

FIGURE 7 is a graph of the horizontal deflecting field along the axis of the yoke when the tabs are in one ex-

2

treme position and when they are in the other extreme position.

The invention will be described in connection with a particular design of a type of a magnetic deflection yoke that is in common use in television receivers, but it should be understood that it can be used with other types of yoke.

As is well understood by those skilled in the art, nearly all the yokes used in television receivers are comprised of four coils of "saddle" configuration such as shown in FIGURE 1. Each coil has end turns 1 that are bent outward at about 90° from the side turns 2. One coil 3 is mounted on top of the neck of a cathode ray tube (not shown) and another coil 4 is mounted on the bottom. Circuits are provided for producing current in these coils that varies from a maximum value in one direction to a maximum value in the other direction so as to produce in the volume between the coils a vertical magnetic field parallel to the axis 6 of the coils. In accordance with well known laws of physics such a vertical magnetic field deflects a beam of electrons directed along the axis 8 of the cathode ray tube (not shown) in a horizontal direction. In a television receiver constructed so as to operate in response to signals presently approved by the F.C.C., the beam scans a series of parallel horizontal lines at the rate of 15,750 a second. Accordingly, means are provided for producing currents in the horizontal windings that vary from maximum to minimum value at the same rate.

30 The other two coils, not shown in FIGURE 1, are similar to the coils 3 and 4 and are mounted on opposite sides of the neck of the cathode ray tube. Circuits are provided for causing current to flow through them that varies from a maximum value in one direction to a maximum value in the other at a frequency of 60 times a second. The horizontal magnetic field produced thereby causes the beam to move downward so that each horizontal line is vertically displaced from the preceding one.

35 The coils may be held in position in various ways but a common method is illustrated in FIGURES 2, 3, 4 and 5. In FIGURE 2 there is shown the bulbous portion 10 of a cathode ray tube that adjoins the neck portion 12. A coil form having a forward flange 12 and a rear hub 14 is mounted over the neck 12 and part of the bulbous portion 10. In this particular view, only the end turns 1 of the vertical deflection coils are visible, the side turns being blocked from view by an annular collar of highly permeable magnetic material. In this view the horizontal deflection coils are not visible because they are mounted, in this particular yoke design, between the coil form and the cathode ray tube. In FIGURES 3, 4 and 5 the rear end turns 1 of the horizontal coils are visible, and in FIGURE 5 the side turns 2 can be seen.

40 Turning now to FIGURE 5, which is a vertical cross section through the axis 18 of the cathode ray tube, it will be observed that the end turns 1 of the horizontal deflection coils extend radially into the top and bottom of the hub 14 of the coil form. Slits 20, only one of which appears in FIGURE 5, are provided on opposite sides of the hub 14. A frame 22, shown in detail in FIGURE 6, fits in the slits 20 and provides a means whereby tabs 24 and 26 may be readily moved toward or away from the neck 12 of the cathode ray tube. The inner edges 28, 30 of the tabs 24 and 26 are semicircular so that when the tabs are in their innermost position, as in FIGURE 3, they are in contact with the neck. Whereas this is not absolutely necessary it does give a maximum amount of control over the width of the area scanned by the beam of electrons. If the tabs 24, 26 are sufficiently resilient, they may be made to retain any adjusted position by making them slightly wider than

the frame 34 so that when bowed so as to fit in the frame they will press against it when released. On the other hand, if the tabs 24, 26 are too rigid to function in this manner, the necessary resiliency can be provided by placing a wavy piece of resilient material 36 between one side of the frame 34 and the tabs 24, 26.

The manner in which the tabs 24, 26 operate to adjust the width of the area scanned by the beam will now be explained with the aid of FIGURES 3, 4, 5 and 7. Although most of the vertical magnetic flux produced by the side turns 2 of the horizontal deflection coils lies between the end turns 1, it is well known that in air a discontinuity in the density of the flux cannot exist so that the lines of flux are close together at one point and nonexistent at an adjacent point. Accordingly, if the tabs are not present, the vertical flux extends rearwardly as indicated by the dotted lines 40 in FIGURE 5 and causes the deflection of the beam of electron to start before the electrons reach the rear end turns 1 of the horizontal deflection coils 3 and 4. The solid line 42 of FIGURE 7 illustrates in general the density of the vertical lines of flux, or in other words the field strength along the axis 18, the approximate location of the end turns 1 being indicated by the vertical lines 44 and 46. When properly adjusted, tabs 24 and 26 reduce the flux to their rear with the result that the field strength along the axis 18 is generally as indicated by the dotted line 52 of FIGURE 7. The angle of deflection is proportional to the area under a curve representing the flux directly along the axis 18 and it can readily be seen that the area under the curve 52 is less than that under the curve 42 by an amount equal to the shaded portion so that the beam is deflected through a wider angle when the tabs 24 and 26 are not present.

The following discussion explains why the curves 42 and 52 are different. With the tabs 24 and 26 widely separated as in FIGURE 4 little change is produced in the distribution of the vertical flux, and, as shown by the arrows 48 the flux paths to the rear of the end turns 1 extend in substantially straight lines across the neck 12. When the tabs 24 and 26 are moved inwardly, as illustrated in FIGURE 3, the flux is bent away from the axis 30 as indicated by the curved arrows 50, and the flux distribution along the axis 18 is as indicated by the dotted line 52. Bending of the flux could be produced by a thin ring of highly permeable material, but this would not prevent the flux flowing outside the ring from creating a fairly strong field at some point on the axis to the rear of the ring. The tabs 24, 26 extend on either side of the neck 12 to a point where the vertical flux extending to the rear of the yoke produces a negligible field at the axis 18. The effect of the tabs on the width of scanning varies in accordance with the position of the tabs, the position shown in FIGURES 3 and 4 being extremes.

The vertical deflection coils also produce flux to the rear of their end turns 1, but the density of the flux and hence the field produced at a point where the axis 18 intersects the plane of the tabs 24, 25 and rearward thereof, is small in comparison with the vertical flux density. Whatever small effect the tabs 24 and 26 have on the vertical dimension of the area scanned by the electron beam is in the same sense as their effect on the horizontal dimension.

The material used for the tabs must have low losses so as to avoid an undue reduction in the Q of the horizontal deflection system. Satisfactory results have been attained with tabs of Sinimax having a thickness of 0.004".

A yoke assembly using the tabs of this invention improves the picture contrast ratio and the focus of the beam of electrons. As can be seen from FIGURE 7, when the tabs 24, 26 are moved inwardly, the centroid of the area is moved forward i.e. the centroid under the curve 52 is further forward than the centroid of the area under the curve 42. This produces a forward shift in

the center of deflection and greatly reduces the tendency of the beam to graze the inner surface of the neck 12 when a raster is being swept.

There is a trend toward making cathode ray tubes of less depth which results in bringing the electron gun close to the rear of the deflection yoke. For reasons understood by those skilled in the art, the magnetic flux defocuses the electron beam, and because the tabs 24, 26 of this invention reduce this flux, they improve the focus.

While I have illustrated a particular embodiment of my invention, it will of course be understood that I do not wish to be limited thereto, since various modifications can be made and I contemplate by the appended claims to cover all such modifications as come within the true spirit and scope of my invention.

What I claim as new and desire to secure by Letters Patent of the United States is:

1. A magnetic deflection yoke comprising a first pair of horizontal deflection coils, a second pair of vertical deflection coils, said second pair of deflection coils being shorter than said first pair, means for mounting said first pair of coils with their axes coinciding and at right angles to the axes of said second pair, said axes of said first pair and said axes of said second pair being perpendicular to a reference axis of said yoke, a width control comprising first and second tabs of highly permeable magnetic material, means for mounting said tabs to the rear of said first pair of magnetic deflection coils to permit said tabs to be moved along a line perpendicular to said reference axis so as to provide a low reluctance path for the portion of the magnetic flux produced by said coils that extends rearward thereof.

2. A magnetic deflection yoke comprising a first pair of saddle type coils, means for mounting said first pair of coils in diametrically opposed relationship so that their axes substantially coincide and their end turns extend in opposite radial directions, a second pair of saddle type deflection coils, means for mounting said second pair of deflection coils so that their axes substantially coincide and are substantially perpendicular to the axes of said first pair, said second pair of coils being shorter than said first pair so that their end turns are closer to the axes of the two pairs of coils, a width control comprising a pair of elongated tabs of thin highly permeable magnetic material, means for mounting said tabs in a plane parallel to said axes of said coils near the end turns of said first pair of coils, said mounting being such as to permit said tabs to be slid along a line in said latter plane that is substantially perpendicular to the axes of said first pair of coils.

3. In a magnetic deflection yoke for a television receiver having first and second pairs of diametrically opposed deflection coils mounted around an axis, so as to produce, when energized, magnetic flux in mutually perpendicular directions each of which is perpendicular to said axis, means for controlling the maximum deflection afforded a beam of electrons passing through said magnetic flux comprising a pair of tabs of highly permeable magnetic material, means for mounting said tabs for movement in a plane, said plane being perpendicular to said axis and adjacent to the ends of said coils, said mounting means also restricting said movement along a line in said plane that is perpendicular to the magnetic flux produced by one of said coils and parallel to the magnetic flux produced by the other.
